(57) **CLAIM**

The ornamental design for a light, as shown and described.

DESCRIPTION

FIG. 1 is a front view of a light in accordance with the present design.

FIG. 2 is a rear view of the light shown in FIG. 1.

FIG. 3 is a left side view of the light shown in FIG. 1.

FIG. 4 is a top view of the light shown in FIG. 1.

FIG. 5 is a bottom view of the light shown in FIG. 1.

FIG. 6 is a perspective view of the light shown in FIG. 1.

FIG. 7 is a front view of the light shown in FIG. 1 in an alternate condition of use.

FIG. 8 is a left side view of the light shown in FIG. 7.

FIG. 9 is a right side view of the light shown in FIG. 7.

FIG. 10 is a top view of the light shown in FIG. 7.

FIG. 11 is a bottom view of the light shown in FIG. 7; and, FIG. 12 is a perspective view of the light shown in FIG. 7. The broken lines in the drawings depict portions of the light that form no part of the claimed design.

1 Claim, 12 Drawing Sheets
